SELF-COOLING BUFFING WHEEL

Samuel Goldberg, Detroit, Mich.

Application October 20, 1948, Serial No. 55,560

4 Claims. (Cl. 51—193)

1

This invention relates to buffing wheels and other similar devices used for abrading purposes. More particularly, this invention relates to a new and improved ventilating and cooling structure for embodiment in abrading devices.

Conventional buffing wheel fabrication consists of building up a wheel from laminated discs or fabric sections and connecting thereto a series of layers or spires of fibrous material. In operation, an abrading compound is frequently applied to the buffing material to assist in cutting or polishing the work material.

Because of the density and heat-retaining properties of the fibrous materials used, buffing wheels must be ventilated and cooled so as to prevent them from running hot since it is well known that fibres lose their tensile strength when they become over-heated and disintegrate quite rapidly thereafter. Also, the melting point of the abrading compounds used frequently lies at some point below 150° F., therefore, it is highly desirable to keep the abrading compound from liquifying in order that the compound retains its normal abrasive properties.

In providing for the ventilation and cooling of buffing wheels, those versed in the art have resorted to several well known procedures. Thus, it is seen to be an old established practice to construct a wheel with an assembly of communicating radially and axially extending air passages for the flow of cooling air through such passages during normal rotation of the wheel assembly.

Designs of buffing wheel structures, as practiced in the art, have been inadequate, however, because air circulation through the passages to the peripheral surface of the buffing wheel has been solely dependent on an inappreciable pressure gradient between the ambient air and the air within the wheel structure or on the centrifugal thrust imparted to the confined air itself by the rotating structure.

These designs have also been impractical because the pressure gradient attained in standard practice has actually been far too small to be effective in forcing a flow of air through a comparatively dense buffing fabric.

According to the present invention, it has been discovered that if in the fabrication of the buffing wheel, the spacer plates comprising a center core are provided with radially disposed louvres comprising, in effect, air pumps in addition to providing means for scooping and directing a flow of air into the interior of the wheel structure, greatly improved operating characteristics will be manifested.

2

It has been found, for example, that consumption of buffs may be materially reduced over standard practice because of the elimination of premature buff casualties through burning and scorching. This is of considerable importance inasmuch as the cost of replacing the expendable fibrous buff material is one of the largest single items of expense in carrying out abrading operations. In addition to the pecuniary economies attendant upon the use of a buffing wheel constructed in accordance with my invention, it has been found that the quality of the work produced has likewise improved so that consistently good, high quality work may be turned out over a longer period of time.

Another object of my invention is to provide an improved structure for conventional fabrication of a buffing wheel to any desired width or tread, the wheel being supported on a rotatable spindle by means of my improved center sections thereby providing for improved air flow and ventilation.

A further object of my invention is to provide a buffing wheel which is economical with respect to manufacturing expense and durable in use.

Another object of my invention is to provide a buffing wheel having improved spacer discs having a perforated axial flange and incorporating therein air pump blades for forcibly ejecting air to the periphery of the buff sections.

The specific nature of the invention, as well as other objects and advantages thereof will appear to those skilled in the art from the following detailed description and the accompanying drawings, which by way of preferred example only, illustrate one specific embodiment of the invention.

On the drawings:

Figure 1 is a fragmentary plan view, showing the completed buffing wheel assembly;

Figure 2 is a cross-sectional view taken substantially on the line II—II of Figure 1.

Figure 3 is a reduced scale plan view of a spacer disc before stamping operations;

Figure 4 is a front elevation of a completed spacer disc; and,

Figure 5 is a full plan view of a completed spacer disc.

As shown on the drawings:

This invention will be described and illustrated in connection with its application to an abrading wheel employing polishing elements formed of fabric material. It will, of course, be understood by those skilled in the art that the principles of this invention are equally applicable to abrading

devices embodying different structural material.

As best shown on Figures 1 and 2 a self-cooling buffering wheel 10 is indicated which rotates as a unit with spindle 12. The buffering wheel assembly is built up from a plurality of spacer plates 11 which are mounted on a reduced portion 12a of spindle 12 and are clamped in firm assembly by a cover plate 14 and a retainer plate 16. Removably supported and centered on the peripheries of spacer plates 11 are buff sections 13. Said buff sections 13 comprise an annular buffering surface as at 17. The fabrication and characteristics of the buff material correspond to any of the various types of buffering sections well known in the abrading art as, for example, sections made up of a laminated structure of bias cotton sheeting fabric or the like.

The end of the spindle 12 may be threaded to receive a nut 18 which is tightened as necessary to clamp the retainer plate 16 which thereby engages the periphery of the outermost spacer plate 11 which, in turn, bears against other spacer plates 11 by pressure engagement with the buff sections 13 and a plurality of enlarged washers 19, the innermost of which engages the periphery of the cover plate 14 which is shouldered against the spindle 12, thereby locking the wheel to the spindle.

The retainer plate 16 originally takes the form of a round metal plate in which a plurality of holes 21 may be formed by punching or drilling preferably on a common axis concentric with the axis of rotation and radially spaced so as to be equidistant from one another. The perforated plate 16 is then shaped, preferably by a method of die stamping, to take a flanged cup configuration as may be seen in Figure 2. In addition to taking on the general configuration outlined by a flanged cup, the portions of the retainer plate 16 surrounding one side of each of the holes 21 are flared outwardly to define a plurality of semi-spherical scoops as at 22. Since the scoops 22 surround the holes 21, it will be apparent that counterclockwise rotation of the buffering wheel 10, using the plane of reference of Figures 1 and 2, will cause air to be caught in the scoops 22 which will forcibly drive or pump the air through the holes 21 into the interior of the buffering wheel 10.

Referring now to Figures 3, 4 and 5, a spacer plate 11 is indicated which originally takes the form of a round blank 11a of sheet or plate metal as shown on Figure 3. A plurality of holes 23 are formed in the blank 11a by punching, drilling or other appropriate means. Holes 23 are radially spaced so as to be equidistant from one another and are disposed on a common center line axis defined by a circle drawn concentrically with the periphery of the blank 11a.

A center hole 24 is also formed in the blank 11a by drilling, punching or other appropriate method.

A plurality of openings 26 are formed by bending or flaring the fins 11b inwardly from the face of the blank 11a (Figure 5). Each of the fins 11b preferably define an essentially plane trapezoidal area bounded on one side by a bend line lying on a radial axis, bounded on the opposite side by a cut line spaced a predetermined distance from the bend line on a second radial axis and bounded on both ends by a pair of cut lines lying on concentric circles spaced a predetermined distance from the center of blank 11a.

Fins 11b are acutely inclined with respect to the plane defined by the blank 11a so as to form an included angle which is preferably about 25°, as may best be seen on Figure 4. It will be observed that the peculiar structure of the spacer plate 11 permits the fins 11b to operate as an air pumping mechanism whenever the buffering wheel 10 is caused to rotate. Thus, air previously introduced into the interior of the buffering wheel 10 is subjected to an increase in pressure.

Blank 11a is further die stamped to take on the dish-like configuration best seen in Figures 5 and 6. It will be seen that the blank 11a is bent inwardly on a predetermined peripheral axis as at 28 (Figure 4) to define an axial flange 11c. Axis 28 is preferably located by constructing a line substantially tangent to the innermost peripheries of holes 23 and concentric with the periphery of the blank 11a. The axial line of bend at 28 extends slightly within the tangential axis defined by the holes 23 to insure that the holes 23 will extend to the bottom of the axial flange 11c. The dish-like configuration is completed by bending blank 11a outwardly on a peripheral axis as at 29 to define a radial flange 11d. Axis 29 is preferably located by constructing a line slightly inside of the outermost peripheries of the holes 23 and concentric with the periphery of blank 11a thereby insuring that the holes 23 extend completely across the width of the axial flange 11c. It will be apparent that the holes 23, after die stamping in the manner described, will assume more or less elliptically shaped openings as may best be seen on Figure 5.

Radial flange 11d is further die stamped with a series of embosses comprising a plurality of upper portions 31 and lower portions 32. The embossed upper portions 31 are arranged in spaced radial alignment so as to come in registry with the holes 23. This arrangement permits the bent shoulder portion 33 lying between the upper portions 31 and the lower portions 32 of the embosses to form a plurality of channels 34 (Figures 2 and 4) which are defined when the oversized washers 19 engage the bearing face formed by the lower embossed portions 32. It should be noted that the channels 34 place the interior of the buffering wheel 10 in communication with the spaces lying between the buffering sections 13.

A hub 11 is also formed in blank 11a by bending the peripheral portion surrounding center opening 24 inwardly as is indicated in Figures 4 and 5. Center opening 24 is preferably held within a rather close dimensional tolerance so as to snugly receive the reduced portion 12a of the spindle 12 (Figure 2) permitting the hub 11e to bear against the spindle 12 thereby lending considerable support to the buffering wheel structure.

In operation, this wheel displays greatly improved ventilating characteristics. Once the buffering wheel 10 is set in operation, the air scoops 22 pump air into the interior of the buffering wheel structure. The interior, of course, comprises a plurality of chambers defined by the individual dish-like spacer plates 11 and these chambers are in communication with one another through the openings 26. Since the cover plate 14 is closed, the air pumped into the buffering wheel interior has no alternative but to seek escape radially outward to the peripheral buffering surface 17. The air pumped into the buffering wheel interior is subjected to an additional increase in pressure by virtue of the pumping action of the fins 11b.

The coaction of the scoops 22 and the fins 11b results in the establishment of a substantial pressure gradient between the air in the interior of the buffing wheel and the ambient air. Therefore, the air under pressure escapes through the holes 23 into the buff sections 13. Inasmuch as the buff sections 13 are quite dense, it will be apparent that only a small portion of the entrained air will seep through the main body portion of the buff sections 13. A far greater proportion of the pressurized air will pass through the holes 23 and through the channels 34 from whence the escaping air stream will be directed between the buff sections 13 against the peripheral buffing surface 17. This phenomenon is, of course, highly desirable since the buffing surface is thus thoroughly ventilated and operating temperatures are drastically reduced. The practical results of using a buffing wheel embodying the structural features of this invention are indeed commendable. It has been found that buffing sections used on a wheel constructed in accordance with my invention enjoy a service life from about 40 to 60% longer than with conventionally cooled buffing wheels. Actual laboratory tests reveal that unit production per buffing section has risen approximately 150% when a buffing wheel embodying my invention is employed.

It will be apparent to those skilled in the art that I have described a novel, improved, self-cooling buffing wheel which not only provides means for pumping air into the interior of the buffing wheel structure, but causes the pressure of the air within the interior of the buffing wheel structure to be greatly increased by the pumping action of blades formed in the center spacer plates whereby air is forcibly ejected outwardly to the peripheral buffing surface.

It will, of course, be understood that various details of construction may be modified through a wide range without departing from the principles of this invention, and it is, therefore, not the purpose to limit the patent granted hereon otherwise than necessitated by the scope of the appended claims and the prior art.

I claim as my invention:

1. In a sectional buffing wheel, a rotatable spindle, a plurality of buff rings, a composite supporting, retaining, air-pumping hub member made of stamped sheet metal for each of said buff rings, each of said hub members having an apertured hub to receive said spindle, an annular supporting means spaced concentrically and outwardly thereof to carry one of said buff rings radially with respect to said spindle, and a flat body portion between said supporting means and said apertured hub, a plurality of axially offset vanes in each of said flat body portions forming air pumping blades to pressurize air in the interior of said wheel and force and direct same radially outwardly, said annular supporting means having a plurality of radially extending air flow passages formed therein to carry the pumped air between the buff rings, said hub member having an opening underlying each vane forming an axial air flow passage through said body portion and clamping plate means to retain said buff section units in co-rotatable assembly with said spindle, said clamping plate means including outwardly extending air scoops forming air pressurizing elements to force air axially under pressure into the interior of said buffing wheel for further pressurization and redirection radially outwardly past said buff

rings by said air pumping blades in each of said hub members.

5 2. A spacer plate for an assembly of buff rings, comprising a sheet material disk portion having a central bore to receive a spindle, an annular supporting means spaced outwardly from and concentrically with said central bore to form an annular support for a buff ring, said disk portion having a vane struck out therefrom at an oblique inclination to form an impeller overlying an aperture, said inclined vane being disposed on said disk portion to impel ventilating fluid both axially and radially of the spacer plate, said supporting means having radially extending air flow passages formed therein to pass the radially directed fluid to the buffing ring, said vaned disk portion forming a stage of a multistage axial compressor for a buffing ring assembly.

10 20 3. A spacer plate for supporting a buff ring section in a sectional buffing wheel, comprising a sheet material disk portion having a central bore to receive a spindle, an axial flange extending concentrically from said disk portion to form an annular support for a buff ring, said disk portion having a vane struck out therefrom on a radial line of bend, said vane overlying an aperture at an acute inclination to said disk portion to impel ventilating air both axially through the aperture and radially toward said axial flange, said axial flange being ported to pass ventilating air to the surrounding buff ring, said vaned disk portion thereby forming a stage of a multistage axial compressor for the sectional buffing wheel as well as a centrifugal air pump.

15 25 30 35 40 45 4. In a sectional abrading wheel; an assembly of spacer plates each comprising a disk portion having a central bore to receive a rotatable spindle, an axial flange extending concentrically from said disk portion, and a spacer ring extending radially outward from said flange; an annular abrading element carried on the axial flange of each spacer plate and laterally positioned by the adjacent spacer ring, said flange and ring providing air ports for ventilating said abrading element; said disk portion of the spacer plates having vanes set obliquely thereto and overlying apertures formed therein, said oblique vanes disposed on said disk portion to impel ventilating fluid both axially through said apertures and radially through said ports, thereby to combine multistage axial compression with centrifugal compression for substantially uniform cooling of said abrading elements; and clamping means for securing the sections of the abrading wheel including a clamping plate ported to admit air to the inlet side of the vaned spacer plates.

60 SAMUEL GOLDBERG.
